UNITED STATES PATENT OFFICE.

LEVI P. GRAHAM, OF DECATUR, ILLINOIS.

DESIGN FOR A MONUMENT.

SPECIFICATION forming part of Design No. 12,938, dated May 23, 1882.

Application filed March 30, 1882. Term of patent 3½ years.

To all whom it may concern:

Be it known that I, LEVI P. GRAHAM, a citizen of the United States, residing at Decatur, in the county of Macon and State of Illinois, have invented and produced a new and original Design for Monuments, of which the following is a specification, and which has never been patented to me, nor to others with my knowledge and consent, in any foreign country.

My design consists in a rustic base, out of which spring a pair of tree-stumps whose interlacing branches form a segmental arch carrying a raised name or other ornament, and surmounted by a Gothic arch formed by the

termination of the uppermost branches.

The entire design may be variously ornamented by plant and animal ornamentation,

and the stumps may be made hollow to receive natural plants.

The number and position of the scrolls may be varied without affecting the principle of my design, which consists in the following peculiarities, which I claim:

1. Rustic base *a*, out of which spring trees *b b*, whose interlacing branches form the segmental arch, surmounted by the Gothic arch, substantially as herein shown.

2. A rustic base provided with scrolls for inscriptions, supporting a pair of tree-stumps whose interlacing branches support a raised name, substantially as herein shown.

Attest:

LEVI P. GRAHAM.

GEORGE A. FERGUSON,

ROBERT W. FERGUSON.
